PULL FOR CABINET DOORS AND THE LIKE

Newton S. Leichter, Los Angeles, Calif., assignor to Ajax Hardware Manufacturing Corporation, Los Angeles, Calif., a corporation of California

Application March 7, 1955, Serial No. 34,900

Term of patent 7 years

(Cl. D10—8)

Fig. 1 is a perspective view of a pull for cabinet doors and the like, embodying my new design;

Fig. 2 is a front elevation thereof;

Fig. 3 is a side elevation thereof;

Fig. 4 is an end elevation thereof;

Fig. 5 is a rear elevation thereof;

Fig. 6 is a cross section on line 6—6 of Fig. 3; and

Fig. 7 is a cross section on line 7—7 of Fig. 3.

I claim:

The ornamental design for a pull for cabinet doors and the like, as shown.
